WILLIAM B. WHITSITT AND WALTER R. HEDEMAN, OF BALTIMORE, MARYLAND.

SUPERHEATER HEADER FOR LOCOMOTIVES.

Application filed August 8, 1923. Serial No. 656,419.

Our invention relates to superheater headers for locomotives.

Among the objects of our invention are:—

To provide a header for locomotives which 5 forms a new article of manufacture inasmuch as it is composed entirely of sheet steel or other suitable material which is first formed in sheets, afterwards cut to appropriate shapes and sizes and then autogenously welded together or secured together by any other suitable process.

To provide a header composed of a metal which has substantially the same composition and physical structure as the bolt which 15 clamps the ball joints to the seats formed therein.

To provide a header composed of a metal which affords a superior bearing for the ball 20 joints of the superheater units.

To provide a header so constructed that the material adjacent the seats thereof is of such strength as will insure the securing of the best union possible when the ball joints 25 of the superheater units are clamped thereto.

To provide a header composed of a material which is more resistant to the action of the gases in the smoke box than headers now in use.

Our improved superheater header thus broadly differentiates from superheater headers which have heretofore been formed of cast metal. It has been found that in casting superheater headers, quite a large 35 percentage of same has been found to be imperfect owing to the fact that the cores shifted during the casting process and that cracks occurred in the walls of the superheater headers owing to unequal contraction during the cooling of same.

After cast headers have been placed in service upon locomotives it has been found that cracks developed between the seats to which the ball joints of the superheater units were clamped. These cracks have been due to the fact that the metal between the seats for the ball joints of the superheater unit is substantially a beam which is subjected to the stress of the bolt that clamps 45 the ball joints to the header and said metal is subjected to varying stresses during heating and cooling, owing to the fact that the header is of cast metal and crystalline in physical structure and the bolt is of wrought metal and fibrous in physical structure.

Moreover, the composition of wrought

metal is such that it compresses better than does cast metal and hence, is capable of a more perfect union with the ball joints. All of the foregoing advantages have been long desired, but have been unobtainable in cast metal headers. These features have been incorporated in our wrought metal header at a minimum of cost.

We will now explain our method for producing our improved header and describe the features of same for illustrative purposes, reference being had to the accompanying drawings.

In the drawings:—
Figure 1 is a perspective view of the bottom plate of our header.

Fig. 2 is a view of the bottom plate, top plate and partition of our header after these parts have been secured together.

Fig. 3 is a top plan view of our completed header.

Fig. 4 is a view of the parts shown in Fig. 3 looking in the direction of the arrow 4 in said figure. In this figure one pair of the ball joints, the yoke and the jaw bolt for clamping said joints to the header are shown.

Fig. 5 is an enlarged view of the means for clamping the superheater units to the header when viewed as in Fig. 4.

Fig. 6 is a view of the parts shown in Fig. 5 looking in the direction of the arrow 6 in said figure.

Fig. 7 is a view similar to Fig. 5 but showing a stud bolt used in place of the jaw bolt shown in Fig. 5.

Fig. 8 is a view of the parts shown in Fig. 7 looking in the direction of the arrow 8 in said figure.

In carrying out our method for the production of our new header we first prepare a substantially flat bottom plate 10 provided with a plurality of bosses 31 on the underside thereof in accordance with one modification for a purpose hereinafter referred to; a top plate 12 which is bent or provided with the angularly disposed or sloping portions 13—13 and the sides 14—14 which portions and sides approximately conform to the curvature of the locomotive smoke box; a corrugated or zig-zag partition 15 or one having a plurality of upright bends therein and adapted to extend substantially the full length of the bottom plate or wall 10; a substantially flat front plate 18 and a substantially flat back plate 19. The front plate is provided with holes

20—20 and the back plate is provided with a hole 21 for purposes hereinafter referred to.

5 The steps of our method are then as follows:—

The bottom edge of the zig-zag partition 15 is welded on both sides of said partition to the top surface of the plate 10. The top edge of the partition 15, which is shaped 10 to conform to the undersurface of the top plate 12, is then welded on both sides to the undersurface of said top plate, angularly disposed portions 13—13 and sides 14—14. The meeting edges of the top and bottom 15 plates are welded together, either as illustrated in Figure 2 or overlapped in the opposite manner. The pipes 22—22 for connecting the superheater header to the locomotive cylinders are preferably passed 20 through the holes 20, with the flanges of said pipes on the inside of the front plate 18, said flanges welded to the inside of said plate, and said pipes are welded to the outside of said plate before said plate is welded 25 to the bottom plate 10, top plate 12, angularly disposed portions 13 and sides 14. The pipe 23 for connecting the superheater header to the dry pipe of the locomotive is preferably passed through the hole 21 with 30 the flange of said pipe on the inside of the back plate 19, said flange welded to the inside of said plate and said pipe welded to the outside of said plate before said plate is welded to the bottom plate 10, top plate 12, angularly disposed portions 13 and side 14. The front plate 18 and back plate 19 are then welded along their edges to the bottom plate 10, top plate 12, and angularly disposed portions 13—13 and sides 14—14. 40 The pipes 24—24 of the superheater unit are provided with ball joints 25 which fit the seats 26 formed in the bottom plate 10. The ball joints 25 are pressed against the seats 26 by the yoke 27 which is under compressive stress from the nuts 28, the latter being threaded on the stud bolt 32 which is mounted in the boss 31.

In using our improved superheater header, it is to be mounted in the smoke box of the locomotive and the pipes 22—22 are to be connected to the cylinders of the locomotive. The pipe 23 is to be connected to the dry pipe.

50 Referring to Fig. 3, the holes 33 at the upper side of the partitions 15 are to be connected to one side of the pipes of the superheater units and the holes 34 at the lower side of said partition are to be connected to the other side of said units. The units are to be mounted in certain of the fire tubes of the locomotive boiler in the usual manner.

55 Referring to Figures 1, 2, 4, 5 and 6, a modified form of connection for the superheater units is there disclosed. In accord-

70 ance with this modification, the bottom plate 10 is provided with slots 11 therethrough and the partition 15 is formed with extensions 16 which are inserted through the slots when the plates are assembled so as to completely fill said slots. The partition is preferably welded to the bottom plate both above and below said plate, as shown particularly in Figure 2. Those portions or extensions 16 of the partition 15 below the bottom plate 10 are formed with a plurality of holes therethrough and these holes serve for connection with the jaw bolts 29 by means of pins 30 inserted through corresponding perforations therein and the holes 17, as illustrated particularly in Figures 5 and 6. The bolts 29 are provided with nuts 28 which serve for tightening the yokes 27 to thereby clamp the ball joints 25 against the seats 26 to hold the pipes 24 of the superheater units in place, as in the embodiment illustrated in Figures 7 and 8.

75 Our improved superheater header operates in the well-known manner, is lighter in weight and yet stronger than the usual cast header. As only bent and no dished sections are used expensive dies are dispensed with. The partition or separator 15, by virtue of its corrugated formation, and welded connection to the top and bottom 80 plates, not only serves to divide the header into two compartments of substantially equal volume, as indicated in Figure 3, but serves as a stay member between top and bottom plates and rigidly trusses the whole 85 structure together.

90 While we have explained one method for producing our improved superheater header and have described one form of superheater header, yet it is to be understood that this is 95 for purposes of illustration only and in no wise to limit the scope of our invention, for changes may be made in the method set forth and in the structure illustrated and described without departing from the spirit 100 of our invention.

105 We claim:—

110 1. The herein described method of forming a superheater header of sheet metal which consists in shaping sheets of metal to form the bottom, top, front, back and partition of said header, welding said partition to said bottom and top, welding said bottom to said top and welding said front and back to said bottom and top.

115 2. The herein described method of forming a superheater header of sheet metal which consists in shaping sheets of metal to form the bottom, top, front, back and partition of said header, welding said partition to said bottom and top, welding said bottom to said top, welding pipes to said front and back and welding said front and back to said bottom and top.

120 3. The herein described method of forming

a superheater header of sheet-metal which consists in shaping metal sheets to form top, bottom, front and rear walls, forming a partition wall of sheet-metal having a plurality of upright bends therein, of a length such that it extends substantially from end to end of said bottom wall, shaping the upper edges thereof so that it conforms to the shape of the top wall, assembling and welding the partition to the top and bottom walls, and finally assembling the front and rear walls therewith and welding the remaining abutting portions of all of the walls to form tight joints therebetween.

4. The herein described method of forming a superheater header comprising shaping metal plates to form top, bottom, front and rear walls, said top wall being formed with downturned end portions extending toward the bottom wall and one of said walls overlapping, and the edge thereof abutting the end of the other wall, forming a partition wall of sheet-metal having a plurality of upright bends therein, of a length such that it extends approximately from end to end of said bottom wall, shaping its upper edge so that it conforms to the lower surface of the top wall, assembling the partition between and welding it to the top and bottom walls, assembling the front and rear walls therewith and welding the meeting portions of said top, bottom, front and rear walls to form tight joints therebetween.

5. The herein described method of forming a superheater header of sheet-metal which consists in shaping metal sheets to form top, bottom, front and rear walls, said top wall having sloping end portions terminating in down-turned portions adapted to overlie the end portions of said bottom wall, forming a partition wall of sheet-metal having a plurality of upright bends therein, of a length such that it extends substantially from end to end of said bottom wall, shaping the upper edges thereof to conform to the shape of the top wall, assembling and welding the partition to the top and bottom walls, assembling the remaining walls therewith, and finally welding the abutting portions of all of said walls to form tight joints therebetween.

6. The herein described method of forming a superheater header of sheet-metal which consists in shaping metal sheets to form top, bottom, front and rear walls, forming a partition wall of sheet-metal having a plurality of upright bends therein, of such a length that it extends substantially from end to end of said bottom wall, shaping the upper edges thereof to conform to the shape of the top wall, welding the partition to the top and bottom walls, welding pipes to said front and rear walls, and finally welding said walls to the top and bottom walls to form tight joints therebetween.

7. The steps in the herein described method of forming a superheater header of sheet-metal plates, which consist in forming a substantially flat bottom plate, welding to said bottom plate in fluid tight relation a corrugated upright partition member, shaping the upper surface of said partition member to conform to a top plate, and welding the partition to said top plate in fluid tight relation.

8. The herein described method of forming a superheater header of sheet-metal plates, which consists in forming a substantially flat bottom plate, welding to said bottom plate a corrugated upright partition member, shaping the upper surface of said partition member to conform to a top plate, welding the partition to said top plate, welding the meeting edges of the top and bottom plates, and finally welding front and back plates to the adjacent edges of said top and bottom plates.

9. The herein described method of forming a superheater header of sheet-metal plates, which consists in forming a substantially flat bottom plate, welding to said bottom plate a corrugated upright partition member, shaping the upper surface of said partition member to conform to a top plate, welding the partition to said top plate, welding the meeting edges of the top and bottom plates, welding a pipe to a back plate and said plate to the adjacent edges of said top and bottom plates, welding a plurality of pipes to a front plate, and finally welding said plate to the adjacent edges of said top and bottom plates.

10. A superheater header composed of sheet metal parts welded together and having a bottom provided with means on the external surface of said bottom for attachment to clamping bolts of superheater units.

11. A superheater header composed of sheet metal parts welded together and having a bottom provided with means welded on the external surface of said bottom for attachment to clamping bolts of superheater units.

12. A superheater header composed of sheet metal parts welded together and having a bottom comprising seats for ball joints, and bosses provided with threaded holes welded to the outside of said bottom, in combination with bolts threaded in said holes, nuts and yokes on said bolts and ball joints of superheater units pressed against said seats by said yokes.

13. A superheater header composed of a plurality of wrought flat plates forming sides, a wrought bottom plate connected thereto, a wrought top plate bent and connected to the end portions of the bottom plate and the top and ends of the side plates, and a partition wall interposed between and connected to

said top and bottom plates, and serving as a stay member therebetween.

14. A superheater header comprising a wrought bottom plate, a wrought top plate and a separator interposed therebetween, the upper and lower edges of said separator abutting the lower and upper surfaces of the said top and bottom plates, and welding means uniting said abutting portions, said separator being provided with a plurality of upright bends therein forming alternately interspaced pockets on opposite sides thereof.

15. A superheater header comprising

front and rear and top and bottom plates, 15 a partition wall extending substantially the entire length of said bottom wall, means for connecting the adjacent portions of said partition to said top and bottom walls to provide a pair of chambers of substantially equal volume, said bottom wall having a plurality of openings therein, and means secured to said bottom wall for fastening pipes to said openings.

20 In testimony whereof, we affix our signatures.

WILLIAM B. WHITSITT.
WALTER R. HEDEMAN.
